UNITED STATES PATENT OFFICE.

CARL BLOCK, OF MERRILL, WISCONSIN.

HORSE-COLLAR.

SPECIFICATION forming part of Letters Patent No. 388,014, dated August 21, 1883.

Application filed January 10, 1883. Serial No. 260,304. (No model.)

To all whom it may concern:

Be it known that I, CARL BLOCK, a citizen of the United States, residing at Merrill, in the county of Lincoln and State of Wisconsin, 5 have invented certain new and useful Improvements in Horse-Collars; and I do declare the following to be a full, clear, and exact description of the invention, such as will enable others skilled in the art to which it appertains to make and use the same.

This invention relates to combined collars and hames; and it has for its objects to provide a means for connecting the sections, also connecting the check-hook, and providing a 15 means for holding the collar in proper position on the neck of an animal. These several objects are attained by the means shown in the accompanying drawings, in which—

Figure 1 is a front view of a combined collar and hames constructed according to my improvements. Fig. 2 is a detail side view of the same. Fig. 3 is a detail vertical sectional view. Fig. 4 is also a sectional detail view. Figs. 5 and 6 are views of the socket-castings 25 for the tops of the collar. Fig. 7 is a view of the check-hook removed. Fig. 8 is a perspective view of the leather placed below the joints of the sockets; and Fig. 9 is a view of the combined check-hook, pin, and buckle.

Referring by letter to the said drawings, A 30 indicate two sections of a collar, which are properly shaped from wood or other suitable material. These wooden sections, which comprise the collar, are faced with metal strips B, which may form the hames, and these strips are provided with the tug-loops and other appliances usually employed in hames for the attachment of the harness.

In the present illustration I have shown two 40 forms of tug-loops—viz., the ordinary loop, a, comprising the two studs b and the bolt passing through eyes therein and having a sleeve, and also a hook, as C, having a spring-snap, as shown, either of which may be used, according to the fancy of the mechanic.

D indicates a metallic socket, which receives the lower meeting ends of the collar-sections. This socket is provided with apertures, and is secured at one end to one of the 45 collar-sections, the opposite section having a spring-actuated lock-bolt, which, when the section carrying it has been let into the said

socket, the lock-bolt will enter the apertures therein and hold the sections together at this point. Thus it will be seen that by depressing the spring-bolt the sections of the collar 55 may be disconnected at their lower ends.

E indicate the hinge-castings for the upper ends of the collar. These castings are hollow and shaped to receive the tops of the 60 collar-sections, and are formed with lug-eyes f to receive a bolt or pintle, whereby the same may be connected by a hinge-joint. These castings, after being slipped over the tops of the sections, are adjusted thereon and secured in position by the threaded shanks of the rings g, which pass through apertures in the said castings and are turned into screw-tapped apertures in the metallic strips or hames B, which are secured to the wooden 70 collar. One of the lug-eyes f is slotted vertically, as shown at h, to receive the lower reduced end, F, of the check-hook G, and this reduced portion is provided with a transverse aperture, i, to receive the hinge-rod or pintle 75 K as it is passed through the lugs of the castings E to connect them. This rod or pintle K, which unites the upper ends of the collar, is threaded at its forward end, as shown at l, and is provided at its opposite end with a 80 buckle, m. It will thus be seen that this rod serves a threefold function—viz., it acts as a pintle to connect the castings E, a bolt or rod to secure the check-hook in position, and a buckle whereby the collar may be connected 85 with the saddle to retain the former in proper position on the neck or shoulders of an animal.

I indicates a shield of leather, although it may be of other material. This shield is suitably shaped to lie beneath and cover the joint formed by the castings E. This shield is also provided at its opposite upturned ends with holes n n, which are designed to coincide with the eyes in the lugs of the said castings E to 90 receive the pintle or hinge-rod, and to the eye on the forward outer side of the collar is secured or formed thereon a nut or screw-tapped seat, r, which receives the threaded end of the said pintle-rod and sustains the 95 same when screwed therein.

In practice it is not necessary that the upper joints should be disconnected or the check-hook removed after once properly connected,

as the collar may be placed on or removed from the neck of a horse by manipulating the spring-bolt at the lower part of the collar.

It will be seen that I have a collar and hames 5 in which the checkrein may be held thereby, and in order to keep the collar properly adjusted on the animal a strap may be employed to buckle with the pintle-rod and connect with the saddle or other suitable part of the harness.

It is obvious that a sweat-pad may be provided for the collar, in which case it would have a suitable number of loops, whereby it may be conveniently attached thereto and readily removed when desired.

Having described my invention, what I claim is—

1. The collar having the hinge sockets at its upper end, in combination with the checkhook having an eye at its lower end and let into the lug-eyes or hinge-barrel, the shield having apertures and a threaded nut in one of

them, and a pintle-rod having a buckle at one end and a threaded portion at its opposite end, substantially as specified.

2. The combination, with a collar composed of two hinged sections, of a pintle for the said hinge having a loop at one end and a hinged tongue to form a buckle, whereby the said pintle may serve a twofold function, substantially as specified.

3. The combination, with a collar having a hinge at its upper ends to unite the sections, of a check-hook having its lower end adapted to enter the barrel of the hinge, and a pintle-rod for the said hinge also passing through and securing the said hook therein, substantially as specified.

In testimony whereof I affix my signature in presence of two witnesses.

CARL BLOCK.
